G. S. DAUGHERTY,
INVENTOR
BY *Victor J. Evans.*
ATTORNEY

UNITED STATES PATENT OFFICE.

GEORGE SAMUEL DAUGHERTY, OF BLUE RIVER, WISCONSIN.

SPARK PLUG.

Application filed January 3, 1921. Serial No. 434,626.

To all whom it may concern:

Be it known that I, GEORGE S. DAUGHERTY, a citizen of the United States, residing at Blue River, in the county of Grant 5 and State of Wisconsin, have invented new and useful Improvements in Spark Plugs, of which the following is a specification.

This invention relates to spark plugs as used in connection with internal combustion 10 engines and an object of the invention is to provide a positive spark plug which is constructed to materially reduce filling of the plug by carbon and a plug which is practically self cleaning.

15 Other objects of the invention will appear in the following detailed description and in the accompanying drawings wherein:

Fig. 1 is a side elevation partly in section of the improved spark plug.

20 Fig. 2 is a horizontal section through the spark plug taken on the line 2—2 of Fig. 1.

Fig. 3 is a fragmentary perspective of the central electrode of the spark plug.

Referring more particularly to the drawing 25 the improved spark plug embodies the usual metal shell 1 provided with a threaded shank 2 adapted for threadable engagement in a cylinder head of an internal combustion engine which shell receives therein

30 the usual porcelain or insulator 3 centrally of which the central electrode 4 of the plug extends. The central electrode 4 of the spark plug is constructed of electricity conducting material and carries the usual wire 35 binding means 5 on its upper end while its lower end 6 is flattened, being substantially rectangular shape in cross section and providing an increased sparking surface 7 at its lower end which is spaced from and co-

40 acts with the disc electrode 8. The disc electrode 8 has a stem 9 formed thereon by means of which the disc electrode is connected to the shell 1. The disc electrode 8

extends horizontally, and is positioned beneath and spaced from the lower sparking 45 end 7 of the central electrode 4 forming the spark gap through which the electric current passes in spark form for igniting the combustible fuel in the cylinder of an internal combustion engine. The disc 8 is 50 greater in diameter than the width of the flattened end 6 of the central electrode 4 as clearly shown in Fig. 2 of the drawing and thus provides a protector for the central electrode to prevent accumulation of carbon 55 thereon the major portion of the carbon about the spark plug will accumulate on the under surface of the disc electrode 8 from which it will be burned by the explosions in the cylinder thereby providing 60 practically a self cleaning spark plug. When the electric current passed into the spark plug is comparatively great a relatively large spark will pass between the electrodes 4 and 8 owing to the shape of 65 the sparking end of the central electrode 4 and in case the current is relatively weak the spark will jump from any portion of the sparking end 7 to the disc 8.

It is, of course, to be understood that the 70 invention may be constructed in various other manners and the parts associated in different relations and, therefore, I do not desire to be limited in any manner except as set forth in the claim hereunto appended. 75

Having thus described my invention what I claim is:

In a spark plug, a central electrode having a rectangularly shaped sparking surface horizontally disposed, a disc electrode 80 arranged horizontally in spaced parallel relation to the sparking surface of the central electrode, and a stem projecting from the disc electrode and secured to the plug.

In testimony whereof I affix my signature. 85
GEORGE SAMUEL DAUGHERTY.
